UNITED STATES PATENT OFFICE.

PATRICK J. DERRIG, OF NORTH WEYMOUTH, MASSACHUSETTS, ASSIGNOR
TO THE AMERICAN AGRICULTURAL CHEMICAL COMPANY, OF NEW
YORK, N. Y., A CORPORATION OF CONNECTICUT

APPARATUS FOR NITRATING SULFUR DIOXID.

No. 850,820.

Specification of Letters Patent.

Patented April 16, 1907.

Application filed September 5, 1905. Serial No. 276,917.

To all whom it may concern:

Be it known that I, PATRICK J. DERRIG, a citizen of the United States, residing at North Weymouth, in the county of Norfolk 5 and State of Massachusetts, have invented an Improvement in Apparatus for Nitrating Sulfur Dioxid, of which the following description, in connection with the accompanying drawings, is a specification, like letters on 10 the drawings representing like parts.

My invention relates to the manufacture of sulfuric acid, and is concerned particularly with improvements in the apparatus for nitrating or supplying the necessary oxids of nitrogen to the sulfur dioxid in the well-known lead-chamber process. The method of nitrating at present practiced in this process consists in providing so-called "niter-pots" within suitable chambers interposed 15 between the pyrites-burner and the flue leading to the Glover tower, these pots containing a mixture of sodium nitrate and sulfuric acid, which when subjected to heat from the pyrites-furnace is decomposed in the presence 20 of air mainly into oxids of nitrogen and sodium sulfate. This method of nitrating by "potting," as it is called, is extremely unsatisfactory, since the heat from the burners frequently causes the above reaction to take 25 place all at once and without the possibility of control or regulation with respect to the varying needs of the process. Furthermore, this process is wasteful and uncleanly and results in the production of the objectionable 30 "niter-cake," which must be effectually disposed of where it can do no harm to surrounding objects.

The object of my invention is to obviate these defects and to that end contemplates 40 furnishing the nitrating material in the form of a solution, the supply of which can at all times be regulated in accordance with the requirements of the process and the residue of which material after nitrating has been effected may be conveniently conducted away 45 and to a storage-receptacle.

My invention will be best understood from a description of one particular embodiment thereof which has herein been selected for the 50 purpose of illustration and is shown in the accompanying drawings, and its scope will be pointed out in the appended claims.

In the drawings, Figure 1 is a view of a portion of the so-called "chamber" apparatus, showing my improved nitrating device interposed between the pyrites-furnace and the Glover tower; and Fig. 2 is a similar view of the apparatus, but showing the nitrating device located between the Glover tower and the first lead-chamber.

In the embodiment of my invention herein selected for illustration the portion of the well-known lead-chamber apparatus shown in Fig. 1 comprises a portion 1 of a bank of pyrite-furnaces of any desired construction 55 and a Glover tower 2, communication between the furnaces and tower being effected through the usual flue 3.

For the purpose of supplying the necessary oxids of nitrogen to the volumes of sulfur dioxid supplied by the pyrites-furnaces to the Glover tower instead of employing the old form of niter-pots within the furnaces 1 I have devised a convenient form of nitrating apparatus; (shown at 4,) which may be located between the furnace 1 and the tower 2, as shown in Fig. 1, or between the tower 2 and the first lead-chamber 5, as shown in Fig. 2. The structure of the nitrating device is in both cases the same, the only difference between the two residing in the direction of flow of the gases therethrough, the flow in the arrangement shown in Fig. 1 being from the bottom to the top of the device and in Fig. 2 from the top to the bottom.

The structure of the device being substantially the same in both cases, a description of one will suffice for both.

Referring to Fig. 1, the device consists of an outer tube or shell supported in any suitable manner, as upon the flue 3, and preferably, but not necessarily, cylindrical in cross-section and of considerably less diameter than the Glover tower, with which it communicates, the proportion being about one to 90 five. The nitrating apparatus may, if desired, communicate directly with the first lead-chamber, as by a pipe 12^a. (Shown in dotted outline, Fig. 1.) Communication is effected between the flue 3 and the bottom of the nitrating device by means of a pipe 6, through which a portion of the sulfur-dioxid gas from the furnaces 1 flows into the base of the nitrating device, the pipe entering the de-

vice just below a grating or grille 7 therein. Supported above the top of the nitrating device 4 is a vessel 8, adapted to contain a solution of sodium nitrate in sulfuric acid, which 5 is supplied to the nitrating-tube through a plurality of small pipes 9, luted into the top plate 10 thereof. The interior of the nitrating-tube is filled with a mass 11 of crushed quartz or coke for the purpose of finely dividing and distributing the entire solution throughout the cross area of the tube 4 to compel the sulfur dioxid entering at the bottom of the tube to pass up through the same in intimate contact with said solution. In 15 its passage up through the nitrating-tube the sulfur dioxid is brought by the quartz or coke filling into intimate contact with the down-flowing solution of sodium nitrate, whereby, owing to the heat of the sulfur gas, the nitrate solution is denitrated, and the combined sulfur dioxid and nitrous fumes pass out of the pipe at the top of the nitrating-tube 4 into and through the upper portion of the Glover tower, from which the gases pass on to the 20 lead-chambers. It is to be understood, however, that the greater volume of sulfur dioxid passes directly from the furnaces through the flue 3 into the Glover tower in the usual manner and is there brought into contact with the 25 nitrous vitriol supplied from the Gay-Lussac tower in a manner well known to those familiar with this process. The supply of sodium-nitrate solution from the vessel 8 to the nitrating-tube 4 may be regulated in any suitable manner, as by a cock 13, located in the 30 tubes 9. The surplus acid flowing from the nitrating-tube 4 is received in a pan 14 at the bottom of said tube and is conducted therefrom by a line of piping 15 to any suitable 35 point—as, for instance, to the vessel 15'.

In an apparatus of the above description nitrating material may be supplied to the lead-chamber apparatus in quantities determined exactly by the needs of the process instead of, as heretofore, in the irregular and frequently extravagant manner incident to the use of niter-pots.

Instead of placing the nitrating device between the pyrites-furnace and the Glover 50 tower it may, if desired, be located between said tower and first lead-chamber, as shown in Fig. 2, in which case the fumes and gases from the Glover tower all pass through the nitrating-tube 4 from the top of the tower to 55 and into the base of the chamber 5 in the usual manner, while at the same time the sodium-nitrate solution from the vessel 2 also passes down in intimate contact with the gases, and the surplus fluid flows away from 60 the nitrating device through the tube 15, as before described.

While the form of my invention here shown comprises the best embodiment thereof now known to me, it is to be understood that the

invention is not confined to the embodiment shown.

I claim—

1. In apparatus for manufacturing sulfuric acid, a furnace for supplying sulfur dioxid, a chamber succeeding thereto and adapted to receive sulfur dioxid from said furnace, a nitrating-chamber in communication with said furnace and with said first-mentioned chamber and adapted to receive sulfur dioxid from said furnace and to conduct the same to 75 said first-mentioned chamber and a receptacle connected with said nitrating-chamber and adapted to discharge thereinto a solution of nitrating liquid, said receptacle being out of free communication with said first-mentioned chamber.

2. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber having an inlet and outlet of relatively small cross-section and adapted to receive sulfur dioxid and to discharge the same, a receptacle connected with said chamber and adapted to discharge thereinto a solution of nitrating liquid, said receptacle being out of free communication with said Glover tower.

3. In apparatus for manufacturing sulfuric acid, a furnace for supplying sulfur dioxid, a Glover tower adapted to receive sulfur dioxid from said furnace, a lead-chamber in communication with said Glover tower, a nitrating-chamber having an inlet and an outlet of materially less cross-section than that of said nitrating-chamber and adapted to receive sulfur dioxid and to discharge the same, a receptacle connected with said chamber and adapted to discharge thereinto a nitrating solution, said receptacle being out of free communication with said Glover tower.

4. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber adapted to receive sulfur dioxid and to discharge the same, a receptacle connected with said chamber and adapted to discharge thereinto a solution of nitrating liquid, said receptacle being out of free communication with said Glover tower, and provisions for conveying surplus acid from the nitrating-chamber to a storage-receptacle.

5. In apparatus for manufacturing sulfuric acid a furnace for supplying sulfur dioxid, a Glover tower adapted to receive sulfur dioxid from said furnace, a lead-chamber in communication with said Glover tower, a nitrating-chamber having an inlet and an outlet of materially less cross-section than that

of said nitrating-chamber and adapted to receive sulfur dioxid and to discharge the same, a receptacle connected with said chamber and adapted to discharge thereinto a nitrating solution, said receptacle being out of free communication with said Glover tower, and provisions for preventing surplus acid from passing into the sulfuric-acid system.

6. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber having a mass of finely-divided distributing material therein, said nitrating-chamber being adapted to receive sulfur dioxid and to discharge the same, a receptacle connected with said chamber and adapted to discharge thereinto a solution of nitrating liquid, said receptacle being out of free communication with said Glover tower.

7. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber adapted to receive sulfur dioxid and to discharge the same, a receptacle connected with said chamber and gravity spraying means for conveying nitrating liquid therefrom to said chamber, said receptacle being out of free communication with said Glover tower.

35 8. In apparatus for manufacturing sulfuric acid, a furnace for supplying sulfur dioxid; a chamber succeeding thereto and adapted to receive sulfur dioxid from said furnace, a nitrating-chamber in communication with said furnace and the said first-mentioned chamber and adapted to receive sulfur dioxid from said furnace and to conduct the same to said first-mentioned chamber, a receptacle connected with said nitrating-chamber and adapted to discharge thereinto a solution of nitrating liquid and means for conducting surplus acid from said nitrating-chamber to a storage-receptacle.

9. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber adapted to receive sulfur dioxid and to discharge the same, a receptacle connected with said nitrating-chamber and adapted to discharge thereinto a solution of nitrating liquid, said receptacle being out of free communication with said Glover tower and means for conducting surplus acid from said chamber to a storage-receptacle extraneous to the sulfuric-acid system.

10. In apparatus for manufacturing sul-

furic acid, a furnace for supplying sulfur dioxid, a Glover tower adapted to receive sulfur dioxid from said furnace, a lead-chamber succeeding said Glover tower and in communication therewith, a nitrating-chamber adapted to receive sulfur dioxid and to discharge the same, a receptacle connected with said nitrating-chamber and adapted to discharge thereinto a regulated quantity of nitrating fluid, said receptacle being out of free communication with said Glover tower and provisions for conveying surplus acid from the nitrating-chamber to a storage-receptacle extraneous to the sulfuric-acid system.

11. In apparatus for manufacturing sulfuric acid, a furnace for supplying sulfur dioxid, a Glover tower adapted to receive sulfur dioxid from said furnace, a lead-chamber succeeding said Glover tower and in communication therewith, a nitrating-chamber adapted to receive sulfur dioxid and to discharge the same, a receptacle connected with said nitrating-chamber and adapted to discharge thereinto a regulated quantity of nitrating fluid, said receptacle being out of free communication with said Glover tower, and means for conveying surplus acid from said nitrating-chamber to a storage-receptacle extraneous to said sulfuric-acid system.

12. In apparatus for manufacturing sulfuric acid, a furnace for supplying sulfur dioxid, a Glover tower adapted to receive sulfur dioxid from said furnace, a nitrating-chamber interposed between and in communication with said furnace and said Glover tower, and a nitrating-solution receptacle connected with said nitrating-chamber and out of free communication with said Glover tower.

13. In apparatus for manufacturing sulfuric acid, a furnace for supplying sulfur dioxid, a Glover tower adapted to receive sulfur dioxid from said furnace, a nitrating-chamber interposed between and in communication with said furnace and said Glover tower, a receptacle connected with said nitrating-chamber and adapted to discharge thereinto a solution of nitrate of soda, said receptacle being out of free communication with said Glover tower, and means for conducting surplus acid from said nitrating-chamber to a storage-receptacle.

14. In apparatus for manufacturing sulfuric acid, a furnace for supplying sulfur dioxid, a chamber succeeding thereto and in communication therewith, a nitrating-chamber adapted to receive sulfur dioxid and to discharge the same, means for conveying to said nitrating-chamber a regulated quantity of nitrating fluid and a conduit for conveying surplus acid from said nitrating-chamber to a storage-receptacle.

15. In apparatus for manufacturing sulfuric acid, a furnace for supplying sulfur di-

oxid, a chamber succeeding thereto and in communication therewith, a nitrating-chamber adapted to receive sulfur dioxid and to discharge the same, means for conveying to said nitrating-chamber a regulated quantity of nitrating fluid, said conveying means being out of free communication with the sulfuric-acid system, and a conduit for conveying surplus acid from said nitrating-chamber

10 to a storage-receptacle.

16. In apparatus for manufacturing sulfuric acid, a furnace for supplying sulfur dioxid, a Glover tower adapted to receive sulfur dioxid from said furnace, a nitrating-chamber interposed between and in commun-

ication with said furnace and said Glover tower, means for conveying to said nitrating-chamber a regulated quantity of nitrating fluid, said conveying means being closed from full receipt of the acid of the sulfuric-acid system and a conduit for conveying surplus acid from said nitrating-chamber to a storage-receptacle.

In testimony whereof I have signed my name to this specification in the presence of 25 two subscribing witnesses.

PATRICK J. DERRIG.
